UNITED STATES PATENT OFFICE.

WILLIAM ROBERT SHAVER, OF COVINGTON, VIRGINIA, ASSIGNOR OF ONE-THIRD TO
ALEX S. ROBERTSON, OF COVINGTON, VIRGINIA.

NEEDLE-VALVE.

1,332,310.

Specification of Letters Patent. Patented Mar. 2, 1920.

Application filed July 2, 1918. Serial No. 243,020.

To all whom it may concern:

Be it known that I, WILLIAM R. SHAVER, a citizen of the United States, residing at Covington, in the county of Alleghany and 5 State of Virginia, have invented certain new and useful Improvements in Needle-Valves, of which the following is a specification.

This invention relates to valves; and the object of the same is to produce improved 10 means for adjusting the needle of a needle valve to restrict the inlet of fluid.

Another object is to provide means for regulating the degree to which said needle may be adjusted.

15 Figure 1 is a vertical sectional view showing the mounting of the needle and the mechanism for projecting it manually and for limiting the degree of adjustment of which it is susceptible.

20 Fig. 2 is a plan view of Fig. 1,

Fig. 3 is an elevation taken from the right side of Fig. 1,

Fig. 4 is a fragmentary detail of a slight modification.

25 In the preferred embodiment of the present invention, about to be specifically described, 1 designates the needle which is reduced at its lower end to a point 2, which coacts with an appropriately shaped seat S 30 at the inlet of the casing P. By my invention I mount the needle slidably within a tubular guide 3 socketed at its lower end at 4 to receive an enlargement or shoulder 5 on the body of the needle so that the latter

35 may not be opened at all beyond a certain extent; and the guide is herein shown as supported by being screwed into the casing P which has a chamber C permitting movement of the shoulder 5. The needle valve 40 or rod rises through packing 6 within an appropriate cavity at the top of the guide, and the rod threaded near its upper portion is shown. At the top of said guide is a tubular barrel 10 having at one side of its 45 upper end an upright notch 11, and within said upper end a shoulder 12 which is annular so as to serve as a seat for the upper cup 13, the same having a pin 14 movable vertically within said notch. The lower

50 cup or washer 16 rests upon the packing 6, and a coiled expansive spring 19 is mounted within the barrel around the needle, its ends bearing respectively against the cups. Above the upper cup 13 a lock nut 17 is screwed 55 onto the threaded portion of the rod or

needle, and at the extreme upper end of the latter is a knob or cap 18.

Surrounding the barrel is a clip 20 supporting a bracket 21 which is forked at its upper end as at 22, and pivoted at 23 within 60 the fork is a lever 24 whereof the lower arm overlies said knob or cap 18 and the upper arm may extend in almost any appropriate direction. In Fig. 1 it is shown as overlying the lower arm, and connected with it 65 is a wire 25 leading to a proper point. In Fig. 4 what would be the equivalent of the upper arm is numbered 26, and the wire 27 leads in the opposite direction. It is the intention that this element 25 or 27 lead to 70 a remote point where it will be within reach of the operator.

With the parts assembled as best seen in Fig. 1, in which the needle is at its upper limit with its shoulder 5 fitting closely 75 within the socket 4 the maximum amount of liquid is passing through the inlet. When desired, the operator draws on the wire 25 or 27 or by some other means moves the lever, and it bears on the cap 18 which 80 pushes the needle downward. This motion carries with it the lock nut 17 which bears on the upper cup 13, and of course the spring 19 is compressed; hence it is necessary to maintain the tension on the wire in 85 order that the restriction in the flow of liquid shall be permanent. It will be seen from Fig. 1 that the needle cannot be pushed downward beyond the point where the lower edge of the periphery of the cup 90 13 strikes the shoulder 12. As this cup is screwed onto the threaded portion of the needle, its adjustment is effected by turning it and then setting the nut 17 above it; yet always leaving the pin 14 projecting into 95 the notch 11 to prevent the cup from rotating, although it may still rise and fall. When the operator pulls on the wire he should be permitted to move the point 2 into the passage surrounded by the seat S 100 only to a certain degree which will not be sufficient to entirely cut off the flow of fluid. Of course release upon the wire permits the parts to again take their original position, when the shoulder 5 rises into the 105 socket 4 and the inlet is wide open. The lever may be given a variety of shapes according to requirement of the case.

The foregoing description and the drawings have reference to what may be con- 110

sidered and preferred, or approved forms of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by 10 Letters Patent, is:—

1. In a needle valve adjuster, the combination with a guide having a socket in its lower end, a needle valve slidably mounted through said guide and having a shoulder 15 seating in the socket when the needle valve is wide open, and packing in the guide around the needle; of manually operable means for moving the needle valve to unseat its shoulder from the socket and to move the 20 valve to closed position, a barrel surrounding the needle, an element adjustably mounted on the needle and coacting with the upper end of the barrel, and a nut on the needle above said element, for the purpose 25 set forth.

2. In a needle valve adjuster, the combination with a guide having a socket in its lower end, and a needle valve slidably mounted through said guide and having a shoulder seating in the socket when the needle valve is wide open; of manually operable means for moving the needle valve to unseat its shoulder from the socket and to move the valve to closed position, a barrel 30 surrounding the needle and seated on said guide, its upper end being internally shou- 35 dered and one wall having an upright notch above the shoulder, a cup screwed on the needle and coacting with the shoulder, a pin 40 on the cup loosely mounted in said notch, a spring bearing the cup upward, and a nut threaded on the needle above said cup.

3. In a needle valve adjuster, the combination with a guide, a needle valve slidably 45 mounted through said guide, and packing in the guide around the needle; of manually operable means for moving the needle valve to closed position, a cylindrical bar-

rel mounted on said guide and having an upright notch in its upper end, a washer 50 within said barrel, a cup coacting with the upper end of the barrel and having a pin loosely mounted in said notch, said needle passing through the washer, barrel and cup, a coiled expansive spring surrounding the 55 needle between said washer and cup, and a nut threaded on the needle above said cup.

4. In a device of the class described, the combination with a vertically adjustable needle, a tubular guide in which it is slidably mounted, means for limiting its upward movement therethrough, a tubular barrel on the guide around the needle and having an upright notch, a cup adjustably mounted on the needle and coacting with the upper end 60 of said barrel, and a pin on the cup moving in said notch; of a nut threaded on the needle above said cup, a cap at the upper end of the needle, a clip embracing said barrel, a bracket rising from said clip and 65 forked, and a two-arm lever pivoted in said fork with one arm overlying said cap and the other adapted for manual operation.

5. In a device of the class described, the combination with a vertically adjustable 75 needle, a tubular guide in which it is slidably mounted, means for limiting its upward movement therethrough, a tubular barrel on the guide around the needle and having an upright notch, a cup adjustably 80 mounted on the needle and coacting with the upper end of said barrel, and a pin on the cup moving in said notch; of a nut threaded on the needle above said cup, a bracket whose lower end is supported on 85 said barrel and whose upper end is forked, a lever pivoted in said fork with one arm overlying the needle, and a wire connected with the other arm and adapted to be led to a remote point, for the purpose set forth. 90

In testimony whereof I affix my signature in presence of two witnesses.

WILLIAM ROBERT SHAVER.
